GODET ARRANGEMENT

John J. Krehbiel, Bridgeport, Conn.

Application May 13, 1938, Serial No. 207,821

5 Claims. (Cl. 18—8)

This invention concerns a godet arrangement, i. e., an arrangement for and a method of conveying spun artificial silk, e. g. from a setting bath to a first point of destination.

For various purposes a path of travel having a certain length is provided for the newly spun silk, as it progresses to a first point of delivery. Stretching is one important operation applied to the spun silk in its first travel. Aside from contemplating a much needed improvement of the stretching of the newly spun silk—and more particularly a ready control thereof—this invention has various other objects. Thus, for instance, the improvements herein are to deliver the spun silk at a uniform speed of travel and offer a control to this end, so that the silk may be spooled or piled in a consistently orderly fashion at all times.

It is an important object of this invention to facilitate the checking or even metering of the condition of a progressing spun silk, and of providing for simple and quick adjustment in the friction and tension, and stretching, slackening, advancing or retarding applied to spun silk, as it progresses.

The method for this invention will therefore not only find ready application in the process of spinning artificial silk, but also in the laboratory, where tests are made on the basis of performance, and where the mechanical handling best suited for manufacture is evaluated by experiments.

Other objects of this invention will be more clearly recognized from the following description thereof.

The exemplary showings of the accompanying drawing is schematic in as much as it is not an illustration of all details of handling spun silk; nor is it in true proportion. The drawing emphasizes the arrangement of godets, more particularly in respect to each other, it being however understood, that godets so arranged may be spaced and applied at any point of travel of a spun silk and in any desired number.

In the drawing:

The schematic elevation of Fig. 1 shows the progress of spun silk from a bath to the spinning pot.

Fig. 2 is a cross-sectioned detail view taken in planes indicated by dot-dash lines in Fig. 1 and in a direction there pointed out by the numeral 2.

The schematic plan view of Fig. 3 indicates the progress of spun silk to a bobbin.

Similar numerals refer to similar parts throughout the various views.

Fig. 1 of the drawing shows a filament 12 to pass from a setting bath 11 over godets mounted on a panel 13 into a collecting and twisting pot 14.

5 The stretching of a filament is a function of the pull applied thereon, such pull being ordinarily applied by one or more godets. The filament is carried over a predetermined angle or arc of the periphery of a godet. The frictional contact applied by said arc of the periphery of the godet upon the filament, and the speed at which said periphery is driven in advance of the speed at which the filament is fed from the setting bath or from an intermediate point determines the 10 pull applied to the filament. If therefore the pull exerted by a godet was to be changed in the prior art; e. g. increased, a mechanical rearrangement has to be brought about; i. e. the speed of revolution had to be increased by a change in the drive, 15 a larger godet had to be substituted, or the shape or physical structure of the periphery of the godet had to be changed, in order to provide for larger friction. Such substitutions or changes of the prior art ordinarily require an interruption 20 of operation. It is an object of this invention to provide for adjustment of the pull of the godets at will, and during operation if so desired.

The pull of a godet may be expressed by, i. e. it is substantially inversely proportional to the ratio 25 of the slip of the filament on the godet. If therefore a greater contact between the filament and the godet is effected, the increased friction will decrease the slip and increase the pull. If we change, therefore, the angle at which a filament 30 is fed onto a godet, the extent of contact of the filament with the godet will change, and slip and pull will be correspondingly altered. Accordingly 35 this invention provides for an adjustment of the angle between the portions of filament extending to and from a godet. Such adjustment may be

40 very effectively brought about, according to this invention, by relatively moving godets particularly transversely past each other, for instance by swinging them in relation to, or revolving them 45 about each other, because the limit of contact of the filament with a godet may be changed many times by such a movement. The godet movement for increased pull will generally be in the direction of the apex of the loop of filament extended over the godet, the path of the filament being incidentally lengthened. For decrease of 50 pull the conditions are the converse.

It has also been found useful, to provide a guide godet, which may for instance be the last godet 55 applied to a filament. Such a guide godet is

preferably applied at a peripheral speed substantially equal to the linear speed at which the filament is to be delivered at a point of destination, or at a speed slightly but predeterminedly in excess of the latter speed. Such a guide godet offers a convenient gauge for determining whether or not the other godets apply the proper pull. By way of contrast to the guide godet these other godets will hereinafter be called pull godets.

For purposes of this invention godets of the usual type may be used, for instance glass godets with a grooved periphery, the periphery having the general appearance of a finally toothed gear. Or any other type of godets offering a uniform slip may be used. But it may also be desirable to select the guide godet with a view of avoiding slip, a solid periphery executed in a better gripping material, such as hard rubber, being for instance in order. Thus the guide godets 15 and 16 are shown to have solid peripheries 17, whereas the pull godets 18, 19, 20, 21 and 22 are indicated by dash lines to be provided with grooved peripheries 23, as it is actually shown on godet 18.

Let the shaft 24 of godet 18 be driven at a predetermined speed, which speed may stand in predetermined relation to the speed of rotation of pot 14. A gear 25 is mounted upon shaft 24 behind the panel 13, and a gear 26 meshes with gear 25 and drives the guide godet 15 in clockwise direction at a peripheral speed, which may be the linear speed at which the filament is to be delivered to the pot 14, or which may slightly exceed the said speed. Then the diameter of the effective periphery of the pull godet 18, which is mounted on shaft 24, is chosen so that the filament pulled by said periphery and slip thereon is delivered to godet 15 substantially at a linear speed equal to the peripheral speed of godet 15. Thus the gear ratio 25-26 and the 40 diameters of the godets 18 and 15 may be selected, for instance, so that the peripheral speed of the godet 18 is about 20 percent larger than that of godet 15.

Godet 19 is also driven from shaft 24, by way 45 of gear 27 meshing in gear 25. Here the gear ratio 25-26 and the ratio of diameters of the godets 18 and 19 may be chosen, so that godets 18 and 19 have substantially the same peripheral speed. However, the peripheral speed of godet 19 may slightly lag behind that of godet 18, if there is a substantial distance between godets 18 and 19, so that a stretching of the filaments passing from the latter to the former might be expected.

According to the drawing the godet 19 is not allocated at a fixed position but its drive extends through a circular slot 28 in panel 13, and it is rotatively mounted upon a swing bracket 29. Swing bracket 29 is fulcrumed upon the hub 30, in which the shaft 24 is journalled, and which hub 30 extends concentrically with the said shaft 24 from the panel 13. In order not to interrupt the closure provided by the panel 13 between the gearing and the back thereof and the operative parts to the front thereof, the swing lever 28 may be executed at a larger disc, as indicated, said disc extending closely over the slot 28.

Swing lever or disc 29 may be swung into various positions around the hub 30, the driving relationship between godets 18 and 19 being preserved at all times by way of the meshing gears 25 and 27. The swing lever or disc 29 may be adjusted and locked in a preferred angular posi-

tion, e. g. by a lock pin 31 which may be tensioned by a suitable spring in one or other of holes 32 in panel 13.

Fig. 1 shows swing brackets or disc 29 to be 5 swung into its extreme position in a clockwise direction, in which position the filament 12 contact with substantially two-third of the periphery of each of the relatively staggered godets 18 and 19. When the swing lever or disc 29 is adjusted in its extreme position in a counter-clockwise direction, the filament 12 contacts less than one-third of the peripheries of the pull godets 18 and 19. Correspondingly much less pull is exerted in the latter case than in the case of the arrangement of the pull godets as shown in Fig. 1. By way of intermediate positions of the swing bracket or disc 29 the stretching pull exerted upon the filament may be adjusted within the range of the extremes just described.

In accordance with the relative adjustment of the two godets 18 and 19 the slackness or tautness of the portion of filament 33 extending between godets 18 and 15 will be changed. By observing the slack obtained at said portion 33 of the filament, we may therefore determine the correct position of swing bracket or disc 29. Such slack may be determined by vision or touch, or by a suitable indicator, for instance by a swing lever with an idler pulley resting upon said portion 33, as known.

Fig. 3 shows a device of this invention applied in multiple, producing several variable stages of stretching. It is of course ordinarily desirable to provide for greater stretching distances, than those here shown.

In the showing of Fig. 1 various speeds of revolution of the different godets were obtained by the gearing. Thus the godets 19 and 15 may be of the same diameter, although the godet 19 has a larger peripheral speed than the godet 15. In the showing of Fig. 3 all godets are driven at the same speed of revolution, a variation of peripheral speed being produced by adjusting the diameters of the various godets.

After the filament 35 has been passed between the pairs 20, 21 and 22 of pull godets and over the guide godet 16 mounted upon panel 36 it is guided by way of a feed 37 onto the bobbin 38. The speed of take up of feed 37 and bobbin 38 is arranged from the start to be substantially the same as the circumferential speed of guide godet 16. Helical gears 40 on the shaft 39 drive gears 41 on the upper godets of the pair of godets 20, 21 and 22 at the same speed of revolution, and the driven gear 41 on the top pull godet 22 drives the guide godet 16 with a similar gear 41 at the same speed of revolution by way of an interposed idler gear 42.

Similarly to the swing lever or disc 29 of Fig. 1 round discs 43, 44, 45 carry the lower ones of pairs of pull godets 20, 21 and 22, said godets being again connected into the chain of gearing by further gears 41 mounted on the respective shafts to the back of the panel 36. The godets of each pair 20, 21 and 22 are shown to be substantially like diameter. Whereas the pairs, compared with each other, are of increasing size, godets 21 being larger than godets 20, and godets 22 being larger than godets 21. Godet 16 is however smaller than godet 22.

Step by step, progressing from pair to pair of pull godets, we may vary the stretching action. The pull or the slip of each pair of godets is controlled by angularly positioning of the discs 43.

44 and 45, respectively. These discs together with the lower godets of the pair 21, 22 may be angularly adjusted by way of handles 46 with pointers 47 directed to an empirical graduation 48 therebelow on panel 36. Eccentric lugs 39 may be used for positioning the discs 43, 44 and 45 in preferred positions.

The discs 43, 44 and 45 are shown in the drawing to be swung substantially to an extreme position in a clockwise direction. In that instance there is very little friction and contact of the filament 35 upon the pull godets 20, 21 and 22. But in the instance of each of the pull godets 20, 21 and 22 the contact of the filament with the pull godet may be increased manifold, by swinging the respective discs 43, 44 or 45 in counter-clockwise direction to a position, where the desired contact and pull is obtained. The effect of an adjustment of discs 43, 44 and 45 may again be tested, for instance by observing the tautness or slackness of the stretch of the filament 35 extending from the upper pull godet 22 to the guide godet 16.

Godets may thus be combined into units, which allow an adjustment of the stretching action at will.

Having thus described my invention by way of two modifications, yet I do not wish to be limited thereby, except as the state of the art and the appended claims may require, for it is obvious that various modifications and changes may be made in the form of embodiment of my invention, without departing from the spirit and scope thereof.

What I claim is:

1. In a spinning apparatus, pairs of godets, movable mountings supporting one of the godets of each of said pairs and allowing it to be angularly adjusted relatively to the other godet of said pair of godets, and a gear drive rotating said godets at fixed speeds at all relative positions of their mounting and rotating the godets of different pairs of said godets at different peripheral speeds.

2. In a spinning apparatus, a feed godet, a pull godet and a guide godet successively interposed in the path of travelling spun silk, a drive rotating said guide godet at a peripheral speed substantially equal to the speed at which the spun silk is to be delivered and said feed godet and said pull godet at a peripheral speed predeterminedly exceeding the peripheral speed of said guide godet, said feed godet serving to deliver silk to said pull godet and being angularly adjustable relatively to and around said pull godet.

3. In a spinning apparatus, a pull godet and a guide godet successively interposed in the path of travelling spun silk, a drive rotating said guide godet at a peripheral speed substantially equal to the speed at which the spun silk is to be delivered and said pull godet at a peripheral speed predeterminedly exceeding the peripheral speed of said guide godet, another godet revolvable around said pull godet and connected to be rotated by said drive.

4. In a spinning apparatus, a delivery godet, a pull godet, a guide godet feeding artificial silk to said pull godet, said pull godet delivering the silk to said delivery godet, said guide godet being movable in a plane substantially normal to the axis of the pull godet around the said axis, so that the angle, at which the silk is fed onto the pull godet, may be adjusted at will, and gearing interconnecting said godets.

5. In a spinning apparatus, a delivery godet, a pull godet, a guide godet receiving artificial silk from said pull godet and delivering it to said delivery godet, said pull godet being movable around the axis of said guide godet in a plane substantially normal to the axis of the pull godet, so that the angle, at which the silk is delivered from the pull godet, may be adjusted at will, and gearing rotating said pull godet and guide godet at substantially like peripheral speeds, but said delivery godet at a lower speed.

JOHN J. KREHBIEL.
